UNITED STATES PATENT OFFICE.

HENRY E. BOYD, OF MCKEESPORT, PENNSYLVANIA.

PROTECTOR FOR THE THREADED ENDS OF PIPES, TUBING, &c.

SPECIFICATION forming part of Letters Patent No. 228,171, dated June 1, 1880.

Application filed March 8, 1880. (No model.)

To all whom it may concern:

Be it known that I, HENRY E. BOYD, of McKeesport, in the county of Allegheny and State of Pennsylvania, have invented a new and useful Improvement in Protectors for the Threaded Ends of Pipes, Tubing, &c.; and I do hereby declare the following to be a full, clear, and exact description thereof.

My invention relates to an improvement in protectors for the threaded ends of all kinds of steam-pipes, casing, and tubing; and it has for its object the protection of the same from injury during transportation and while being handled.

Heretofore the usual method of protecting the threaded ends of such pipes, casing, and tubing has been by inserting in the end of the pipe wooden plugs provided with large heads extending beyond the outer circumference of the pipe, so as to keep the threaded end of the pipe from coming in contact with adjacent objects. This method is, at best, far from satisfactory, both by reason of its inefficiency, and also because the plugs are apt to become loose and fall out of the end of the pipe.

By the use of my improved protector or guard the threaded end of the pipe is completely protected from injury.

My invention consists in a cap, guard, or protector composed of an inner coil of wire of a proper size to fit into or between the threads of the pipe and to project slightly above the edges of the same, covered on the outside with a thin sheet of lead or a strip of cloth which has been dipped in asphaltum or other like substance, and over this an outer casing of sheet-iron or light iron pipe, the several parts being evenly and compactly joined by being subjected to the action of a press.

I will now describe my invention so that others skilled in the art may manufacture the same, reference being had to the accompanying drawings, forming a part of this specification, in which—

Figure 1 is a perspective view of my protector. Fig. 2 is a sectional view, and Fig. 3 is a detached view of the clamp for holding the ends of the outer casing of my improved protector together.

a represents the coil of wire, either round or angular, which forms the thread. Over this

is the sheet of lead *b*, or other suitable substance for holding the wire in form, and over this is placed a piece of thin pipe or sheet-iron, *c*, provided with slots *d*, through which the lead is caused to project in the form of lugs *e*. *f* is a longitudinal seam on the outer side of the casing *c*, formed by folding the ends thereof.

The mode of constructing my guard or protector is as follows: A piece of wire is wound between the threads of a steel mandrel. This mandrel should be of the same size as the pipe for which the guard is intended, and should have a thread cut thereon of the same size and pitch as that of the pipe, so as to form the coil *a*. Around this coil is then placed a piece of sheet-lead cut to the required size to enfold the coil *a*. This forms the inside casing *b*. The object of this is to form a casing around and between the wire which forms the thread *a*, so as to hold it in form and shape, and prevent the coil from being separated or enlarged; and instead of lead any other suitable substance, such as cloth covered with asphaltum, which will sink between the rings of the coil, so as to perform the requisite function, may be employed. Over and around the inner casing, *b*, is placed or bent a piece of thin pipe, or a piece of sheet-iron, so as to form the casing *c*. This iron or pipe is provided with one or more slots, *d*. The mandrel is then placed in a press and the parts are firmly compressed together. The effect of this is that the wire is firmly embedded in the coating *b* of lead or other suitable substance. The lead is forced through the slots *d*, so as to form lugs or projections *e* even with the outer surface of the iron casing *c*. The ends of the outer casing, *c*, are folded and pressed together so as to form a secure joint or fastening, and at the same time form a longitudinal projecting seam on the outer surface of the casing *c*, and the guard or protector is contracted so as to fit the pipe for which it is intended. The front end or edge of the iron casing is then bent or folded down sufficiently to protect the wire thread *a*.

Before the casing or guard is placed in the press care must be taken to draw the ends of the wire which forms the thread *a* between the overlapping or meeting ends of the casing *c*, so that they will be firmly held therein when the parts are compressed together.

The object of the seam *f* is to enable the protector to be screwed and unscrewed easily upon and from the pipe by means of a wrench. It may be formed by several different modes of bending the casing *c*. They may be folded together, or they may be bent from each other, so as to form a double flange, which flanges are coupled together by a tapering slide, *h*, which is driven over, engages, and draws the two ends firmly together after the protector has been placed upon the pipe.

The protector should be made longer than the thread of the pipe for which it is intended. This is accomplished by making the outer casing, *c*, of a greater length than the inner coating, *b*, thereby completely protecting the threads of the pipe.

The advantages of my protector are that it is cheap and light, yet, having sufficient strength, it effectually protects the threaded end of the pipe.

Having thus described my invention, what I claim, and desire to secure by Letters Patent, is—

1. A protector or guard for the threaded end 25 of pipes or tubing, consisting of a metal case having an inner coating of soft metal, cloth, or asphaltum, and a wire coil forming a thread therein, so constructed as to fit closely around the end of the pipe or tubing, substantially as 30 and for the purpose specified.

2. A protector for the threaded ends of pipes, provided with a slot or slots, in combination with an inner coating of soft metal or similar substance, substantially as and for the purpose specified.

3. A protector for the threaded ends of pipes, tubes, &c., consisting of a metal casing having a longitudinal seam and a lining of soft metal connected to the casing, substantially as and for the purpose specified.

In testimony whereof I, the said HENRY E. BOYD, have hereunto set my hand.

HENRY E. BOYD.
